PAPER FEEDING MECHANISM

John G. Vergobbi, Quincy, Mass., assignor to
Pneumatic Scale Corporation, Limited, Quincy,
Mass., a corporation of Massachusetts

Application February 5, 1937, Serial No. 124,205

8 Claims. (Cl. 93—12)

This invention relates to paper feeding mechanism.

The invention has for one of its objects to provide a novel and highly efficient paper feeding and gluing device for a package forming machine, and particularly a carton or bag forming machine which is adapted for use in the production of cartons or bags provided with paraffin coated paper liners.

10 A further object of the invention is to provide a novel and highly efficient feeding mechanism for feeding paraffin coated paper.

With these general objects in view and such others as may hereinafter appear, the invention 15 consists in the paper feeding device as embodied in a package forming machine and in the various structures, arrangements and combinations of parts hereinafter described and particularly defined in the claims at the end of this specification.

20 In the drawing a sufficient portion of a packaging machine embodying the invention has been illustrated as will enable the different features of the invention to be understood, wherein Fig. 1 is a diagrammatic view of the paraffin paper feeding mechanism embodied in the present machine; Fig. 2 is a detail view partly in section of the first pair of feeding rolls of the paraffin paper feeding mechanism; Fig. 3 is a similar view of 25 the second pair of feeding rolls; and Fig. 4 is a sheet of paraffin paper showing the location of the strips of adhesive, to be referred to.

25 In the packaging machine forming the subject matter of the present invention, provision is made for forming the package, such as a carton or bag, by wrapping a sheet about a forming block 10, and for folding and sealing the bottom portions of the carton or bag. Inasmuch as the details of such bag forming and carton forming mechanism are well-known and of themselves 30 constitute no part of the present invention, the forming block 10 has been illustrated as mounted upon the usual rotary spider 12 of a machine of this type. When paraffin paper is to be used 35 as the liner for a carton or bag, provision is made for feeding a sheet of such paper to a cut-off knife to the end that an individual sheet may be formed and wrapped about the forming block 10 prior to the wrapping and forming of the carton or bag upon the forming block. The present 40 invention contemplates feeding mechanism for feeding a strip of paraffin paper to the usual cut-off knife of a packaging machine of the character described to the end that successive sheets 45 of the paraffin paper of substantially equal length

5 may be cut off. Prior feeding devices of which I am aware have all been provided with metal rollers, and in attempting to use such prior feeding devices upon the paraffin coated paper substantial variations have been experienced in the lengths of paraffin paper cut off by the cut-off knife. This has seriously interfered with the successful and practical operation of the machine.

10 Referring now to the drawing, wherein the improved feeding apparatus is shown in connection with a known form of bag forming or package making machine, 13 represents a roll of waxed or paraffin coated paper which is fed over an idler 14 and between rollers 15, 16 to a second 15 pair of feed rollers 17, 18. The rollers 15, 16 and the roller 17 are driven continuously in any usual or preferred manner through chain and sprocket drives from a continuously driven shaft, not shown, the rollers 15, 16 being geared together 20 by spur gears 19, 20. The roller 18 is in frictional contact with the loosely rotatable roller 17 and is driven at a higher rate of speed than the first set of rollers 15, 16.

25 The rollers 17, 18 move the strip of paraffin paper forward to a folding table 22, of well-known construction, below the forming block 10 upon which the severed sheet is to be subsequently wrapped. In order to hold the strip stationary to effect the severing of a sheet from the strip, the usual holding fingers 25, located in advance 30 of the rollers 17, 18, and only one of which is shown, are provided. The fingers 25 are caused to rock at the proper time to hold the sheet between the fingers 25 and a shelf 26, by a cam 27, 35 mounted on a cam shaft 29, through connections including a lever 31, connecting rod 33, a two armed lever 35, the second arm 37 of which is provided with a cam roll 39 cooperating with the cam 27. The usual spring connection, not shown, 40 is provided to hold the cam roll 39 against its cam 27. The fingers 25 and the lever 31 are formed integrally and are loosely mounted upon the shaft 41. The holding fingers are provided with rubber faces 28 adapted to contact with the paraffin paper to interrupt the further feeding 45 of the strip while a cutter 30 in cooperation with a stationary blade 32 operates to sever a sheet from the strip. The cutter 30 may be operated by any usual means, not shown, and is positioned immediately beyond the rollers 17, 18. During the cutting operation the continuously rotated roller 18 slips over the paper while the rollers 15, 16 continue to feed the strip which forms a slight loop as illustrated of sufficient 50

length to permit the rapidly revolving roller 18, in cooperation with the frictional contact roller 17 to feed the strip forward to the folding table 22 at the succeeding cycle of operations, when the holding members 25 are lifted. In order to obtain the desired accuracy in the length of the succeeding sheets being cut, the comparative rate of feed of the rollers 15, 16 and the rollers 17, 18 is preferably such that when the holding fingers 25 are raised, the entire slack of the strip (as shown in dotted lines in Fig. 1) is taken up so that the strip will be taut between the two sets of rollers (as shown in full lines), when the holding fingers 25 are again lowered to hold the strip for the cutting operation.

As herein shown, provision is made for raising the frictional contact rollers 17 during the time that the strip is held stationary by the holding fingers 25, in order to relieve the pressure of the rollers 17 against the continuously driven roller 18, thereby eliminating the possibility of accumulating paraffin upon the roller 18 from the paraffin paper. The rollers 17 are mounted upon a shaft 43 which is supported in slots 45 in bearings 41. The ends of the shaft 43 extend beyond the bearings and are engaged by lifting fingers 49 on either side. The lifting fingers 49 are secured to the shaft 41 and are rocked by a cam 50, mounted on the cam shaft 29, through connections including a lever 54 keyed to the rocker shaft 41, connecting rod 56, a bell-crank 58, the other arm 59 of which is provided with a cam roll 60 cooperating with the cam 50.

In practice when attempt was made to feed paraffin paper by the usual forms of paper feeding mechanism embodying steel rollers the paraffin rapidly built up on the steel feed rolls with the result that the severed sheets varied greatly in length. When embodied in a wrapping machine this defect seriously interfered with the successful operation of the machine.

In accordance with the present invention, see Fig. 2, the roller 16, which is suitably mounted in bearings 34 in the machine frame, is provided with a rubber covered surface 36 and in cooperation therewith a plurality of narrow cork covered rolls 15 are provided and as a result in the operation of the mechanism the paraffin strip is fed at a uniform rate of speed without collecting or building up paraffin from the paper passing therethrough upon any of the rollers.

Referring now to Fig. 3 the rapidly revolving roller 18 is formed in part of metal and in part of rubber, herein shown as rubber inserts 38. In operation the roller 18, in cooperation with the light metallic friction roller 17 is effective in feeding the paraffin paper forward at a constant rate of speed, without slippage, when the holding fingers 25 are not in operation to the end that uniform lengths of severed sheets may be produced. On the other hand, when the holding members 25 are in contact with the paper to hold the same stationary, the roller 18 slips over the paraffin paper without interfering in any way with the subsequent feeding operation during the next cycle of the machine. In other words, the gripping characteristics of the feed rollers are such as to alternately feed the material and slip over the material without the accumulation of paraffin on the feed rollers and consequently sheets of uniform length may be produced. During the operation of the machine, the rollers 17 are raised directly after the holding fingers 25 come down and are lowered again immediately preced-

ing the releasing of the strip, when the fingers 25 are raised.

The usual adhesive applying device, generally indicated at 40, may be provided for applying adhesive to those parts of the sheet which will overlap during the subsequent folding or wrapping operation around the forming block 10 and as herein shown comprises a glue roll 42 running in a glue pan 44, in cooperation with an applying roll 46. The rolls are driven from the feed roll 16 through cooperating gears not shown.

As herein shown, see Fig. 4, the strip of paraffin paper is provided with adhesive along the longitudinal edge at 62, a short space at each end of the sheet being left without adhesive, this space corresponding to the position where the sheet is to be severed thus preventing an accumulation of glue upon the cut-off knife 30. Adhesive is also applied at 64, laterally of the sheet, of a length corresponding to one width and one thickness of the lining to be formed. These adhesive strips are applied by the roller 46, which is provided with the circumferential surface 66, interrupted at 68, to provide the spacing between the longitudinal adhesive strips, and a laterally extended narrow surface 70 which applies the lateral strip 64. Inasmuch as the adhesive is applied to the strip of paraffin paper in a definite location with relation to the severed sheet, it will be seen that any variation in the rate of feed would be detrimental to the alignment of the severed sheet. An accumulation of paraffin upon the feeding rolls would have the effect of increasing the surface speed of the feed rollers and thereby cause an incorrect length to be fed. The above described feeding mechanism permits the strip to be accurately indexed for severing successive sheets uniformly.

While the preferred embodiment of the invention has been herein illustrated and described, it will be understood that the invention may be embodied in other forms within the scope of the following claims.

Having thus described the invention, what is claimed is:

1. In mechanism for feeding paraffin paper to a cutter, in combination, a pair of continuously driven feed rolls comprising an elongated paper supporting lower roll of non-metallic material and a relatively narrow upper roll of cork, a second pair of feed rolls spaced from the first pair and comprising a driven paper supporting roll having its surface composed in part of material capable of exerting a relatively efficient gripping effect upon the paraffin paper and in part of a material capable of exerting a relatively inefficient gripping effect upon the paraffin paper, a light upper pressure roller cooperating therewith, and a holding device positioned in advance of the second pair of rolls and adapted to cooperate with the paraffin paper being fed by the first pair of rolls to terminate the movement of the paraffin paper through the second pair of rolls to thereby permit the cutter to cut the paper while the latter is substantially stationary.

2. In mechanism for feeding paraffin paper to a cutter, in combination, a pair of continuously driven feed rolls comprising an elongated paper supporting lower roll of non-metallic material and a narrow upper roll of cork, a second pair of feed rolls spaced from the first pair and comprising a driven paper supporting roll forming the lower roll and having its surface composed in part of material capable of exerting a relatively high gripping effect upon the paraffin paper and

- in part of a material capable of exerting a relatively low gripping effect upon the paraffin paper, a light non-driven pressure roller comprising the upper roll, and a holding device positioned in advance of the second pair of rolls and adapted to cooperate with the paraffin paper being fed by the first pair to terminate the movement of the paraffin paper through the second pair of rolls to thereby permit the cutter to cut the paper while the latter is substantially stationary, means 5 for lifting the upper of said second pair of feeding rolls when said holding device is operated, the frictional characteristics of the lower of said second pair of feeding rolls being such as to permit paraffin paper to slip between the rolls when said holding device is operated and to effectively feed said paraffin paper when the holding device is inoperative.
3. In mechanism for feeding paraffin paper to a cutter, in combination, a pair of continuously driven feed rolls comprising an elongated paper supporting lower roll having a rubber surface and a relatively narrow upper roll of cork, a second pair of feed rolls spaced from the first pair and comprising a driven paper supporting roll having its surface composed in part of material capable of exerting a relatively efficient gripping effect upon the paraffin paper and in part of a material capable of exerting relatively inefficient gripping effect upon the paraffin paper, a light upper pressure roller cooperating therewith, and a holding device positioned in advance of the second pair of rolls and adapted to cooperate with the paraffin paper being fed by the first pair of rolls to terminate the movement of the paraffin paper through the second pair of rolls to thereby permit the cutter to cut the paper while the latter is substantially stationary.
4. In mechanism for feeding paraffin paper to a cutter, in combination, a pair of continuously driven feed rolls comprising an elongated paper supporting lower roll having a rubber surface and a narrow upper roll of cork, a second pair of feed rolls spaced from the first pair and comprising a driven paper supporting roll forming the lower roll and having its surface composed in part of material capable of exerting a relatively high gripping effect upon the paraffin paper and in part of a material capable of exerting a relatively low gripping effect upon the paraffin paper, a light non-driven pressure roller comprising the upper roll, and a holding device positioned in advance of the second pair of rolls and adapted to cooperate with the paraffin paper being fed by the first pair to terminate the movement of the paraffin paper through the second pair of rolls to thereby permit the cutter to cut the paper while the latter is substantially stationary, means for lifting the upper roll of said second pair of feeding rolls, the frictional characteristics of the lower of said second pair of feeding rolls being such as to permit paraffin paper to slip between the rolls when said holding device is operated and to effectively feed said paraffin paper when the holding device is inoperative.
5. In mechanism for applying adhesive and feeding paraffin paper to a cutter, in combination, a pair of continuously driven feed rolls comprising an elongated paper supporting lower roll of non-metallic material, a plurality of spaced relatively narrow upper rolls of cork, an adhesive applying device arranged to apply adhesive to laterally spaced portions of said paraffin paper, said cork rolls being disposed to engage portions of the paper between the applied adhesive, a second pair of feed rolls spaced from the first pair and comprising a driven paper supporting roll having its surface composed in part of material capable of exerting a relatively efficient gripping effect upon the paraffin paper and in part of a material capable of exerting a relatively inefficient gripping effect upon the paraffin paper, a light upper pressure roller cooperating therewith, and a holding device positioned in advance of the second pair of rolls and adapted to cooperate with the paraffin paper being fed by the first pair of rolls to terminate the movement of the paraffin paper through the second pair of rolls to thereby permit the cutter to cut the paper while the latter is substantially stationary.
6. In mechanism for applying adhesive and feeding paraffin paper to a cutter, in combination, a pair of continuously driven feed rolls comprising an elongated paper supporting lower roll of non-metallic material, a plurality of spaced relatively narrow upper rolls of cork, an adhesive applying device arranged to apply adhesive to laterally spaced portions of said paraffin paper, said cork rolls being disposed to engage portions of the paper between the applied adhesive, a second pair of feed rolls spaced from the first pair and comprising a driven paper supporting roll forming the lower roll and having its surface composed in part of material capable of exerting a relatively high gripping effect upon the paraffin paper and in part of a material capable of exerting a relatively low gripping effect upon the paraffin paper, a light non-driven pressure roller comprising the upper roll, and a holding device positioned in advance of the second pair of rolls and adapted to cooperate with the paraffin paper being fed by the first pair to terminate the movement of the paraffin paper through the second pair of rolls to thereby permit the cutter to cut the paper while the latter is substantially stationary, means for lifting the upper roll of said second pair of feeding rolls, the frictional characteristics of the lower of said second pair of feeding rolls being such as to permit paraffin paper to slip between the rolls when said holding device is operated and to effectively feed said paraffin paper when the holding device is inoperative.
7. In mechanism for applying adhesive and feeding paraffin paper to a cutter, in combination, a pair of continuously driven feed rolls comprising an elongated paper supporting lower roll having a rubber surface, a plurality of spaced relatively narrow upper rolls of cork, an adhesive applying device arranged to apply adhesive to laterally spaced portions of said paraffin paper, said cork rolls being disposed to engage portions of the paper between the applied adhesive, a second pair of feed rolls spaced from the first pair and comprising a driven paper supporting roll having its surface composed in part of material capable of exerting a relatively efficient gripping effect upon the paraffin paper and in part of a material capable of exerting a relatively inefficient gripping effect upon the paraffin paper, a light upper pressure roller cooperating therewith, and a holding device positioned in advance of the second pair of rolls and adapted to cooperate with the paraffin paper being fed by the first pair of rolls to terminate the movement of the paraffin paper through the second pair of rolls to thereby permit the cutter to cut the paper while the latter is substantially stationary.

8. In mechanism for feeding paraffin paper to a cutter, in combination, a pair of continuously driven feed rolls comprising an elongated paper supporting lower roll of non-metallic material and a narrow upper roll of cork, a second pair of feed rolls spaced from the first pair and comprising a driven paper supporting roll forming the lower roll provided with a plurality of yieldable rubber inserts therein, a light non-driven pressure roll comprising the upper roll and a holding device positioned in advance of the second pair of rolls and adapted to cooperate with the paraffin paper being fed by the first to termi-

nate the movement of the paraffin paper through the second pair of rolls to thereby permit the cutter to cut the paper while the latter is substantially stationary, and means for lifting the upper roll of said second pair of feeding rolls, the frictional characteristics of the lower of said second pair of feeding rolls being such as to permit paraffin paper to slip between the rolls when said holding device is operated and to effectively feed said paraffin paper when the holding device is inoperative. 5 10

JOHN G. VERGOBBI.
